UNITED STATES PATENT OFFICE.

GEORGE W. CAMPBELL, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

1,407,982.

Specification of Letters Patent. Patented Feb. 28, 1922.

Application filed June 15, 1918. Serial No. 240,146.

To all whom it may concern:

Be it known that I, GEORGE W. CAMPBELL, a citizen of the United States, residing in Hartford, in the county of Hartford and State of Connecticut, have invented certain new and useful Improvements in Typewriting Machines, of which the following is a specification.

This invention relates generally to line-locking mechanism for typewriting machines.

An object of my invention is to provide for compactness, lightness, low cost and ease of production, which are particularly desirable in machines of the small, portable type.

I provide a lightly constructed slidable member mounted on the case-shift frame of the machine and operable when the typewriter carriage reaches the end of a line, said member co-operating with a locking bar to lock the keys. Simplicity of construction, lightness, and a minimum number of parts are sought.

Another feature of my invention is that the signal, usually provided on typewriting machines for notifying the operative when the carriage is about to reach the end of a line, is mounted directly upon the marginal stop.

With my construction, many of the parts which heretofore have formed the connection between marginal stops and signaling devices, are eliminated, and thus lightness, simplicity and low cost of manufacture are obtained.

Other features and advantages will herein-after appear.

In the accompanying drawings,

Figure 1 is a sectional side view of a typewriting machine, showing my invention applied thereto.

Figure 2 is a sectional top plan view of the machine shown in Figure 1, parts being omitted and broken away to show the underlying structure.

Figure 3 is a rear view of the machine, showing the left marginal stops carrying the signaling device and means for operating said device.

Figure 4 is a fractional front view, showing the right marginal stop as seen from the front.

Figure 5 is a detail fractional view, show-

ing a type key and means for locking said key at the end of a line.

Figure 6 is a sectional view through the left marginal stop, showing the structure.

Figure 7 is a diagrammatic rear view, showing the position of the parts just before the signal is to be operated.

Figure 8 is a view similar to Figure 7, showing the position of the parts when the signal is operated.

Figure 9 is a view similar to Figure 7, showing the position of the parts when the carriage is arrested at the end of its travel.

Figure 10 is a view similar to Figure 7, showing the position of the parts when the carriage is moved beyond the left marginal stop.

Figure 11 is a fractional, isometric, perspective view, showing the mechanism for locking the keys when the carriage reaches the end of its travel.

Type keys 15 (Figure 1) actuate bell-cranks 16, which, through links 17, swing type-bars 18 upwardly and rearwardly against a platen 19 mounted on a carriage 20, which travels in letter-feeding direction at 80 the actuation of said keys, the latter actuating a universal bar 21 at each key stroke to actuate an escapement mechanism indicated in general at 22, which controls the carriage 20 in its letter-feeding movements. The carriage is mounted to travel on a case-shift frame 23 shiftable at the depression of shift keys 24.

To arrest the carriage 20, there is provided a left marginal stop 30 (Figures 2, 3, and 6 to 10, inclusive) adjustable at letter-space intervals on a rack 31 slidably mounted at the rear of the shift frame 23, and provided with a projection 32 against which the end of a lever 33 fulcrumed on the rear bar of 95 the typewriter carriage at 34 abuts when said carriage reaches the end of its travel, said rack mounted in proximity to said lever.

To lock the type keys 15 at the end of the carriage travel, the bar 31, on which the marginal stop 30 is mounted, is connected with a slidable link 35 (Figures 1, 2, 3, 9 and 11) to form a sliding frame, which, through the intermediary of connections presently to be described, automatically locks the keys 15 against depression until the locking mechanism is manually released.

For this purpose, the bar or rack 31 has slots 36 (Figures 3, 4 and 7 to 11, inclusive) formed at either end, through which pass screws 37 at the ends of brackets 38 fast to to 5 the shift frame 23.

When the lever 33 on the carriage strikes the projection 32 on the left marginal stop 30, further letter-feed movements of the carriage will slide said bar 31 leftwardly and 10 therewith the slidable link 35 (Figure 9), so that a downwardly-extending arm 43 thereon will rock a bell-crank 39 pivoted at 40 to the stationary machine frame, to swing an arm 41 (Figures 2 and 11) of said bell-crank underneath the universal bar 21 (Figure 5) in control of the escapement mechanism 22, so as to prevent the depression of said bar and thereby prevent depression of any type key, and also locking the carriage 15 20 against letter-spacing or letter-feeding movements. The stop-carrying slidable member or bar 31 and the slidable link 35 therefore form both a carriage-locking device and an operating device for the key-locking member or bell-crank lever 39. The arm 43 is of sufficient length to accommodate the up-and-down movements of the case-shift frame.

To prevent bending the bell-crank arm 41, 30 due to its lightness, at the depression of a type key 15, the effective end of said arm moves in a slot 42 (Figures 5 and 11) formed in a bracket 44 and is supported thereby.

The shift frame 23 at the rear thereof includes a vertical plate having therein an opening 45 through which the slide 35 extends into a position for its arm 45 to operate the key-locking device or bell-crank lever 39. The slide 35 is guided upon this 40 rear vertical plate of the shift frame 23 by means of a screw 46 passing through a slot 46^a in the slide 35, as shown in Figures 1, 2 and 3.

To notify the operative when the carriage 45 20 and type keys are about to be locked at the end of a line, a signal in the form of a bell 48, is provided.

For lightness and simplicity of structure, 50 the bell 48 (Figures 1, 2, 3 and 6 to 10, inclusive) is directly attached to the left marginal stop 30 by a bracket 49 and is struck by a bell-clapper 50 mounted on the end of a wire spring 51 fast to the lever 33 near its fulcrum 34 (Figure 2). To actuate the bell-clapper, the marginal stop 30 is provided with a one-way cam 52 (Figures 1, 2, 3 and 6 to 10, inclusive) placed so as to raise the lever 33, as in Figure 7, against the pressure of a spring 47 (Figures 3 and 9) when the carriage 20 travels in letter-feeding direction, and to abruptly drop said lever, as in Figure 8, so that the bell-clapper 50 will strike the bell 48 and rebound, thereby leaving said bell free to vibrate.

65 To permit the return of the typewriter

carriage after sounding the bell 48, the cam 52 is swingably mounted on a stud 53 (Figures 1, 2, 3 and 6) fast to the left marginal stop 30, and is held by a spring 54 against a pin 55 also fast on said stop, to hold the cam 70 when the end of the lever 33 is moving there-over in letter-feeding direction. When the carriage 20 and lever 33 are moved in anti-letter-feeding direction, the end of the lever will engage the back of the cam 52 and swing 75 said cam about the stud 53 and against the tension of the spring 54. When the end of the lever 33 passes said cam, the latter will be returned to its normal position by said spring.

To unlock the keys 15 and the carriage 20 when arrested by the left marginal stop 30 so that typing may be performed beyond the end of the line, as determined by this marginal stop, the lever 33, which is mounted at 85 the rear of the carriage, is provided with a key 60, (Figures 1, 2, 3 and 9), which, when depressed, raises the left end of the lever above the projection 32 of the left marginal stop, as seen in Figure 10. This permits a 90 spring 61 (Figures 2, 3, 9 and 11) anchored to the shift frame 23 and attached to the sliding link 35 to retract the latter and therewith the bar 31, so as to move said projection out of engaging relation with the lever 95 33 and to permit a spring 62 (Figures 1, 2 and 11) to return the bell-crank 39 to its ineffective position, thus unlocking the type keys and the carriage.

At the completion of a line of writing, the 100 carriage 20 may be returned to the beginning of a new line, and is arrested in its return movement by the left end of the lever 33 engaging a right marginal stop 65 (Figures 1, 2, 3, 4 and 9) also adjustable at letter-space 105 intervals on the slidable bar 31 at the rear of the shift frame. When the carriage is thus returned, the bar 31 and link 35 connected therewith are returned by their spring 61 to normal position, and the arm 41 of 110 the bell-crank 39 is returned to its normal ineffective position by its spring 62 from underneath the universal bar 21, thereby unlocking the type keys.

To adjust the marginal stops 30 and 65 115 along the bar 31, each stop is provided with a finger-piece 66 integrally formed with a C-shaped transversely movable dog member or slide 67, which has integrally formed thereon a pawl or dog 68 (Figure 7), which 120 normally engages teeth 69, formed on the bar 31. When the finger-piece 66 is depressed against the power of a spring 70, the slide is moved downwardly to disengage the pawl 68 from the teeth of the bar 31, to permit 125 the marginal stops to be moved along said bar to any desired position. The slides 67 are guided on the marginal stops by guides 71, integrally formed with the marginal stops. It will be noted that the marginal 130

stops may be moved inwardly, or towards each other, without depressing the finger-piece 66, the pawl 68 snapping over the teeth 69 of the bar 31, but the spring 70 is strong enough to hold said stops against accidental displacement inwardly. The marginal stops are, however, positively held from being moved outwardly by the pawl 68 abutting against one of the teeth 69.

10 The marginal stops 30, 65 and their slides 67 are preferably formed of sheet-metal and thereby simplicity and economy are attained.

15 Variations may be resorted to within the scope of the invention, and portions of the improvements may be used without others.

Having thus described my invention, I claim:

1. In a typewriting machine, the combination with type-keys and a traveling carriage, of marginal stops for arresting said carriage at the beginning and at the end of a line, a case-shift frame on which said carriage travels to be shifted thereby, a slidable member on said shift frame to shift therewith and on which said marginal stops are mounted, and a device mounted upon the frame of the machine for locking said keys at the end of said line, said key-locking device being operable by said slidable member for locking said keys in any case-position of said shift frame.

2. In a typewriting machine, the combination with type keys, of a traveling carriage, a marginal stop for arresting said carriage at the end of its travel, a case-shift frame on which said carriage travels, a slidable member for said marginal stop mounted on said case-shift frame, a universal bar underlying said keys and actuatable at the depression of said keys, and a lever mounted on the framework of the machine and operable by said slidable member at any position of said case-shift frame and co-operating with said universal bar for locking said keys at the end of the carriage travel in any position of said carriage.

3. In a typewriting machine of the class described, the combination of a case-shift frame, a carriage frame on said shift frame and having a platen and comprising a rear bar behind the platen, a lever pivoted upon said rear bar and extending therealong and provided with a key, a rack mounted upon said shift frame in proximity to said lever, and margin-controlling devices independently adjustable along said rack and each having means engageable by said lever to lock the carriage so as to control the extent of margin, said lever operable to disengage said means for unlocking the carriage.

4. In a typewriting machine of the class described, the combination of a case-shift frame, a carriage frame on said shift frame and having a platen and comprising a rear

bar behind the platen, a lever pivoted upon said rear bar and extending therealong and provided with a key, a rack mounted upon said shift frame in proximity to said lever, and margin-controlling devices independently adjustable along said rack and each having means engageable by said lever to lock the carriage so as to control the extent of margin, said lever operable to disengage said means for unlocking the carriage, one of said margin-controlling devices carrying a bell arranged between said rack and said shift frame.

5. In a typewriting machine of the class described, the combination of a case-shift frame, a carriage frame on said shift frame and having a platen and comprising a rear bar behind the platen, a lever pivoted upon said rear bar and extending therealong and provided with a key, a rack mounted upon said shift frame in proximity to said lever, margin-controlling devices independently adjustable along said rack and each having means engageable by said lever to lock the carriage so as to control the extent of margin, said lever operable to disengage said means for unlocking the carriage, said rack movable endwise by said carriage and lever, a slide attached to said rack and extending downwardly, means upon said shift frame to guide said slide, said slide having a downwardly projecting arm, and a key-locking lever in the path of said arm; said arm being of sufficient length to accommodate the shifting movement of said shift frame.

6. The combination of a carriage, a shift frame together with which the carriage is shiftable up and down to different case positions, a rack, a margin-controlling device upon said rack, said rack movable endwise by said carriage, a slide attached to said rack and extending downwardly, means upon said shift frame to guide said slide, said slide having a downwardly projecting arm, a key-locking lever in the path of said arm; said arm being of sufficient length to accommodate the shifting movement of said shift frame, and a spring connected to said slide to retain it to normal position together with said rack.

7. In a typewriting machine of the class described, the combination of a case-shift frame, a carriage frame on said shift frame and having a platen, a rack mounted upon said shift frame, a lever on said carriage frame, margin-controlling devices independently adjustable along said rack and each having means engageable by said lever to control the extent of margin, said rack movable endwise by said carriage and lever, a slide attached to said rack and extending downwardly, means upon said shift frame to guide said slide, said slide having a downwardly projecting arm, and a key-locking lever in the path of said arm; said arm being

of sufficient length to accommodate the shifting movement of said shift frame; said shift frame comprising a vertical plate and having an opening through which said slide extends to position to operate said key-locking lever.

8. The combination of a carriage, a shift frame together with which the carriage is shiftable up and down to different case positions, a rack, a margin-controlling device upon said rack, a lever on said carriage, said rack movable endwise by said carriage and lever, a slide attached to said rack and extending downwardly, means upon said shift frame to guide said slide, said slide having a downwardly projecting arm, and a key-locking lever in the path of said arm; said arm being of sufficient length to accommodate the shifting movement of said shift frame.

9. The combination of a case-shift frame, a carriage thereon, a margin gage to co-operate with said carriage, a slide controlled by said margin gage, an arm connected to said slide, and a key-locking mechanism mounted on the framework of the machine and including a part in the path of said arm, whereby the actuation of the slide by the carriage operates through said arm to lock the keys; said arm being lengthened to accommodate the case-shifting movements of said frame.

10. The combination of a frame mounted to shift up and down, a carriage mounted to travel on said frame, a margin-gage device to co-operate with said carriage, an arm actuatable by said margin-gage device, and a key-locking mechanism mounted on the stationary framework of the machine and including a part in the path of said arm, whereby the actuation of the margin-gage device by the carriage operates through said arm to lock the keys; said arm being lengthened to accommodate the case-shifting movements of said frame.

11. The combination of a frame shiftable to different case positions, a carriage traveling on said frame, a letter-spacing universal bar operable by the type keys, a normally ineffective lock for said universal bar, said lock and said universal bar mounted upon the stationary framework of the machine, and an arm carried by said shift frame to engage said lock, and operable by said carriage to move said lock to effective position, said arm lengthened to accommodate the case-shifting movement of said frame.

12. The combination of a frame shiftable to different case positions, a carriage traveling on said frame, a margin-gage rack movable by said carriage, a letter-spacing universal bar operable by the type keys, a normally ineffective lock for said universal bar, said lock and said universal bar mounted on the stationary framework of the machine,

and an arm moving with said shiftable frame and connected to said rack to engage said lock to move it to effective position, said arm lengthened to accommodate the case-shifting movements of said frame.

13. In a typewriting machine having type-keys, the combination of a case-shift frame, a carriage mounted to travel on said frame, a slide mounted for endwise movement on the case-shift frame, a margin-gage on the slide to co-operate with the carriage, an operating member connected with said slide to move therewith, and a key-locking mechanism mounted on the framework of the machine and including a part in the path of said member, whereby the actuation of the slide by the carriage operates through said member to lock the type-keys, said member having a sliding engagement with said part to accommodate the case-shifting movements of said frame.

14. In a front-strike typewriting machine having type-keys, the combination of a case-shift frame mounted to shift up and down, a carriage mounted to travel on said frame, a margin-gage device to co-operate with the carriage, an operating member on the case-shift frame operable by said margin-gage device, and a key-locking mechanism mounted on the stationary framework of the machine and including a part in the path of said operating member, whereby the actuation of the margin-gage device by the carriage operates through said operating member to lock the type-keys, said operating member having vertical sliding relationship with said part to accommodate the case-shifting movements of said frame.

15. In a typewriting machine having type-keys, the combination of a frame shiftable to different case-positions, a carriage traveling on said frame, a letter-spacing universal bar operable by the type-keys, a normally ineffective lock for said universal bar, said lock and said universal bar being mounted upon the stationary framework of the machine, and an operating member carried by said shift frame and operable by the carriage to move said lock to effective position, said operating member having operating connection with said lock to accommodate the case-shifting movements of said frame.

16. In a typewriting machine having type-keys, the combination of a frame shiftable to different case-positions, a carriage traveling on said frame, a margin-gage member mounted on the shift frame to be moved by the carriage, a letter-spacing universal bar operable by the type-keys, a normally ineffective lock for said universal bar, said lock and said universal bar being mounted upon the stationary framework of the machine, and an operating member moving with said shiftable frame and operable by said margin-

- gage member to move said lock to effective position, said operating member having operating connection with said lock to accommodate the case-shifting movements of said frame.
17. In a front-strike typewriting machine having type-keys, the combination of a case-shift frame mounted to shift up and down, a carriage mounted to have letter-spacing travel on said frame, a letter-spacing universal bar mounted upon the stationary framework of the machine, a normally ineffective key-locking member pivoted upon a vertical axis on the stationary framework of the machine and movable into locking engagement with the universal bar to prevent letter-spacing actuation thereof, and an operating device carried by the shift frame to be operated by the carriage in its letter-spacing movement and having a vertical sliding engagement with said key-locking member so as to operate said key-locking member in all case-positions of the carriage and its shift frame.
18. In a front-strike typewriting machine having type-keys, the combination of a case-shift frame mounted to shift up and down, a carriage mounted to have letter-spacing travel on said frame, a letter-spacing universal bar mounted upon the stationary framework of the machine, a normally ineffective key-locking bell-crank lever pivoted upon a vertical axis on the stationary framework of the machine and having a laterally-extending locking arm movable into locking engagement with the universal bar to prevent letter-spacing actuation thereof and having a rearwardly-extending actuating arm, and an operating arm connected to and extending downwardly from said slide and having a vertical sliding engagement with the actuating arm of said key-locking bell-crank lever so as to operate said key-locking bell-crank lever in all case-positions of the carriage and its shift frame.
19. In a front-strike typewriting machine having type-keys, the combination of a case-shift frame mounted to shift up and down, a carriage mounted to have letter-spacing travel on said frame, a stop-carrying bar movably mounted on the case-shift frame, a margin-stop adjustable along said bar and engageable by the carriage in its letter-spacing movement to move said bar, a letter-spacing universal bar mounted upon the stationary framework of the machine, a normally ineffective key-locking bell-crank lever pivoted upon a vertical axis on the stationary framework of the machine and having a laterally-extending locking arm movable into locking engagement with the universal bar to prevent letter-spacing actuation thereof and having a rearwardly-extending actuating arm, and an operating
- member connected to said stop-carrying bar to be moved thereby and having a vertical sliding engagement with the actuating arm of said key-locking bell-crank lever so as to operate said key-locking bell-crank lever in all case-positions of the carriage and its shift frame.
20. In a front-strike typewriting machine having type-keys, the combination of a case-shift frame mounted to shift up and down, a carriage mounted to have letter-spacing travel on said frame, a stop-carrying slide mounted to have endwise movement laterally on the case-shift frame, margin-stops independently adjustable along said slide, a manually-operable member movably mounted on the carriage and normally engageable with said stops but releasable therefrom, said slide being slidable by the engagement of said member with one of said stops, a letter-spacing universal bar mounted upon the stationary framework of the machine, a normally ineffective key-locking bell-crank lever pivoted upon a vertical axis on the stationary framework of the machine and having a laterally-extending locking arm movable into locking engagement with the universal bar to prevent letter-spacing actuation thereof and having a rearwardly-extending actuating arm, and an operating arm connected to and extending downwardly from said slide and having a vertical sliding engagement with the actuating arm of said key-locking bell-crank lever so as to operate said key-locking bell-crank lever in all case-positions of the carriage and its shift frame.
21. In a front-strike typewriting machine having type-keys, the combination of a case-shift frame mounted to shift up and down, a carriage mounted to have letter-spacing travel on said frame, a letter-spacing universal bar mounted upon the stationary framework of the machine, a normally ineffective key-locking bell-crank lever pivoted upon a vertical axis on the stationary framework of the machine and having a laterally-extending locking arm movable into locking engagement with the universal bar to prevent letter-spacing actuation thereof and having a rearwardly-extending actuating arm, an operating member carried by the shift frame to be operated by the carriage in its letter-spacing movement and having a vertical sliding engagement with the actuating arm of said key-locking bell-crank lever so as to operate said key-locking bell-crank lever in all case-positions of the carriage and its shift frame, and a support for the free end of the locking arm of said key-locking bell-crank lever to prevent the downward yielding of said locking arm by pressure of the universal bar.
22. In a front-strike typewriting machine having type-keys, the combination of a case-shift frame mounted to shift up and down,

GEORGE W. CAMPBELL.
